CLAIM

The ornamental design for a phone case, as shown and described.

DESCRIPTION

FIG. 1 is a perspective view including a front, top and one side of the phone case;

FIG. 2 is an elevational view of the front of the phone case of FIG. 1;

FIG. 3 is an elevational view of the rear of the phone case of FIG. 1;

FIG. 4 is an elevational view of the opposite side of the phone case of FIG. 1;

FIG. 5 is an elevational view of the side of the phone case of FIG. 1;

FIG. 6 is a plan view of the top of the phone case of FIG. 1;

FIG. 7 is a plan view of the bottom of the phone case of FIG. 1; and,

FIG. 8 is a perspective view including a rear, bottom and opposite side of the phone case.

1 Claim, 6 Drawing Sheets
